TO DEMPSTER MILL MANUFACTURING COMPANY, OF BEATRICE, NEBRASKA, A COR-
PORATION OF NEBRASKA

WELL CASING JOINT

Application filed March 7, 1929. Serial No. 345,152.

This invention relates to certain improvements in well casing joints; and the nature and objects of the invention will be readily recognized and understood by those skilled in the arts involved in the light of the following explanation and detailed description of the accompanying drawing illustrating what we at present consider to be the preferred embodiments or mechanical expressions of our invention from among various other forms, arrangements, combinations and constructions of which the invention is capable within the spirit and the scope thereof.

The casing employed for and in wells is constructed or manufactured in sections of any suitable or desired lengths, which sections are and must be joined, connected, or coupled together end to end at and in the well to form the casing therefor and therein. The connecting and coupling of the sections together at the well presents considerable difficulties and problems with the prevailing methods and constructions which render this operation unsatisfactory and an expensive one in time and labor with frequent inefficient joints or connections between the sections resulting. With the larger diameters of casing, the ends of the sections are generally riveted together to form the coupling or joint therebetween, and the riveting is usually carried out by swinging or placing a workman down in the joined sections to back up the rivets at the joints as they are positioned and riveted from the outside of the casing by another workman. This method is not satisfactory, and with the smaller casing diameters which make it impossible to locate a workman therein, the riveting of the sections together is rendered impractical and inefficient.

The present invention holds as a particular object the elimination of the difficulties and disadvantages encountered in the coupling and connecting of well casing sections together by the provision of a design and construction of well casing joint which embodies a mechanically simple yet efficient fastening means through the medium of which the ends of well casing sections designed in accordance with the invention, can be quickly fastened and secured together by a single workman

from the outside of the casing to form the required substantially leak-proof joint between the sections; and the invention further holds as a general object thereof, the provision of such a joint and the fastening means thereof, which is so designed as to be capable of general application to and use with all types of piping, tubing and such like, for securing and joining sections thereof together.

Another object of the invention is the provision of a design and construction of fastening members for securing and joining the sections of well casing together to form a secure, tight joint between the sections, which members are insertable and can be secured in joint forming position and relation in the sections from the exterior of the casing, and are applicable to use on and with all types of well casing, as well as for use with various types and constructions of piping or tubing generally, to secure sections thereof together.

With the foregoing general objects and certain other objects and results in view which will be readily recognized from the following description, the invention consists in certain novel features in construction and in combinations and arrangements of parts, as will be more fully and particularly referred to and specified hereinafter.

Referring to the accompanying drawing:

Fig. 1 is a view in elevation of a section of well casing constructed in accordance with certain features of the invention.

Fig. 2 is a view in elevation of a make-up section of casing embodying the invention, and providing a relatively short section for use in building up a length of jointed casing where a shorter length than the section of Fig. 1 may be required.

Fig. 3 is a detail fragmentary view of a joint of the invention formed between casing sections, a portion of the joint being broken away and in vertical section, and showing the fastening members of the invention in applied, joint forming position securing the ends of the sections together.

Fig. 4 is a detail fragmentary view in elevation of the joint formed between connected sections at the interior of the casing, and

showing a fastening member in position securing the sections together.

Fig. 5 is a view in side elevation of a fastening member or bolt for securing the casing sections together to form the joint therebetween.

A form and adaptation of the principles and various features of the invention is shown in the accompanying drawing and described herein, purely by way of example and not of limitation, as applied to and used in connection with well casing of the riveted sheet metal types, but it is to be understood that those features of the invention incorporated in the casing, as well as those features presented by the fastening or joint forming elements, are not confined to such types or constructions of casings, but are capable of general application to casing of other types where similar or equivalent conditions prevail, as well as application to and use with piping or tubing generally, of any type for any purpose, and the invention contemplates and includes such other uses and adaptations.

In Fig. 1 of the drawing a section of well casing 10 is shown, which section may be and is herein termed for the purposes of this description, a standard or "regular" section of well casing, as manufactured and delivered to and at the well. The regular section 10, in the example hereof, is formed of a series of sub-sections 11 constructed of sheet metal, or other suitable material, bent or otherwise formed to provide the relatively short, tubular lengths or sections of casing with their side seams formed by rivets or the like 12. The sections 11, in this instance, are slightly tapered and are fitted together end to end by inserting the tapered end of one section 11 into the larger end of the next section, so that these ends overlap and are then riveted together by rivets 14, or other suitable fastening means, to form the regular section 10. The sections 11 are so joined or secured together with the riveted side seams of adjacent sections disposed at opposite sides of the regular section, or staggered, as will be clear from Fig. 1, and in the example here shown the regular section 10 is formed of three of the sections 11, although any desired number of sections may be employed to provide a regular section of the required length. The casing section 10 is formed with one end thereof swaged out or enlarged to provide the bell or end socket 15, as shown particularly in Fig. 1, with no intention of limiting the invention to such end formation.

In accordance with one feature of the invention, what for purposes of the present description is referred to as a "make-up" section 20, is provided. This section 20 (See Fig. 2) is of a shorter length than the referred to regular sections 10, and in the present example is formed of sheet metal or other suitable material, in the same manner

as sections 11, or otherwise if desired, with a side seam formed by rivets 21. One end of the make-up section 20 is flared or swaged out to provide the enlarged bell mouth or socket 22 for receiving the plain end of another section, while the opposite end of section 20 is plain to fit into the socket of another section. The purpose of the make-up section 20 is to provide a short section of casing which can be used to complete the length of casing in a well, or other installation of the casing, where a regular section may be found too long; or where for ease of installation and machine operation the use of a short section or sections may be found desirable or expedient. The relatively short make-up sections 20 thus eliminate the necessity of cutting the sections 10, or of cutting the rivets thereof, in the field and making provision for fastening together the cut or reduced length sections.

In forming a well casing from the sections 10, a section is disposed for mounting in a well with its plain end uppermost, and another section 10 is then mounted thereon with the socket 15 thereof fitted over and receiving the plain end of the other section, after which the fitted ends of the sections are fastened together to connect the sections and form a suitable joint therebetween. These operations are continued and sections 10 are added and joined together until the desired length or depth of casing in the well is secured, a make-up section or sections 20 being added at any point or points if found desirable, and joined with the adjacent sections in the same manner as the sections 10.

The invention further provides as a fundamental principle and feature thereof, the elimination of the difficulties encountered in connecting or securing the sections of well casing together and in forming the joints therebetween, so that all of these operations can be performed from the exterior of the casing to produce the desired rigid, substantially leak proof joint between the casing sections. In carrying out this feature of the invention, each end of a regular section 10 is provided with a series of similar spaced slots 17 disposed circumferentially therearound and transversely through the portion thereof overlapped by, or overlapping, the ends of adjacent sections to which they are connected and joined, respectively, that is, slots 17 are formed through the plain end of each section 10, and through the flare or wall of the bell 15 formed at the opposite end. Each make-up section 20 is formed with exactly similar slots 24 therearound at the opposite ends thereof, and spaced the same distance apart as the slots 17 in the sections 10. (See Fig. 2.) The slots 17 at each end of a section 10 are formed and positioned so that they are accurately uniformly spaced apart around the casing and the same accu-

rate spacing is also carried out with slots 24 of a make-up section 20. In assembling and fitting the sections 10 together, and a section or sections 20 when employed therewith, the slots in the joined ends of the sections can thus be readily alined and the sections placed in their required relative positions fitted together for connection and jointing.

Fastening or bolting members or elements 30 (see Fig. 5) are provided, capable of insertion in and through alined section slots from the exterior of the casing, and for operation to bolt and tightly secure the overlapped ends of the casing sections together to form the rigid, substantially leak proof joint therebetween. In the embodiment of these members 30 presented herewith as an example, each comprises a bolt or stem 31 of a diameter to pass through the slots 17 or 24, and having a T head 32 at one end thereof (see Figs. 3 and 4) of a length and width permitting such head being passed through slots 17 or 24, when disposed longitudinally of the slots. The bolt or stem 31 is formed with a squared or flat faced portion 33 (see Fig. 3) adjacent its inner or head end, which portion is of such dimensions as to fit into the slots 17 or 24 and engage the side walls thereof to prevent turning or rotation of the stem, while the outer end length of the stem is exteriorly screw threaded to receive a nut 34. A washer 35 is also provided for fitting over and receiving the bolt or stem 31 of each member 30, and for disposition on the stem 31 between the head 32 thereof and nut 34, for a purpose and to secure a result appearing and explained hereinafter.

Referring now to Figs. 3 and 4 of the drawings, with the ends of two of the sections 10 overlapped and the respective slots 17 thereof alined, the sections are tightly secured and coupled together by the bolting or fastening members 30 to form a tight joint between the section ends, in the following manner. A fastening member 30, with washer 35 and nut 34 screwed on stem 31 and placed at the extreme end of the stem opposite head 32, is inserted inwardly from the exterior of the casing through each opening formed through the overlapped ends of the sections 10 by the alined slots 17, with the head 32 thereof innermost, and disposed longitudinally of the slots so as to pass freely therethrough to the interior of the casing. Each member 30 is inserted a sufficient distance through the slots to clear the squared portion 33 of the bolt from engagement with the slots, and the bolt is then turned to position the head 32 transversely of the slots and the bolt drawn outwardly to bring the squared portion 33 thereof into the slots to hold the member 30 against rotation. With the members 30 in the foregoing position in the slots held against rotation, each nut 34 thereof is then screwed in-

wardly thereon to draw the heads 32 into engagement with the inner side of the casing and force the washers 35 against the outer side of the casing, over and closing the slots 17 and binding and joining the overlapped ends of the sections together to form a tight, rigid joint therebetween. With a fastening member 30 secured in and through each pair of the alined slots 17, spaced around the lapped ends of the sections, a tight joint is formed between the sections, which are tightly and rigidly secured together, while the washers 35 close and seal the slots to prevent leakage, or passage of sand, grit, dirt and the like, and thus form a substantially leak-proof joint between the casing sections.

When a make-up section 20 is used with casing sections 10, the fastening members 30 are employed in the manner above described to secure the sections together and form the required joint therebetween. In using the make-up section 20, one end thereof is overlapped by, or overlaps the adjacent section end, as the case may be, and the slots 24 of section 20 are alined with slots 17, respectively, of a section 10, for example. The members 30 are then employed to make the joint therebetween.

By the use of the fastening or bolting members 30 of the invention, the casing sections can be quickly and efficiently connected and joined together at the well as the casing is put down thereinto, by a single workman from the exterior of the casing without requiring special or expensive equipment. The workman simply inserts the fastening members 30 in the casing slots and then tightens them into joint forming relation and position, all from the exterior of the casing, thus eliminating the difficulties hereinbefore discussed in the installation of well and the like casings. The fastening members 30 are capable of low cost manufacture and can be applied to well casing of the standard or conventional types by the mere addition to such casing sections of the required slots. While socket ends have been shown formed on the sections 10 and 20, such ends are not essential, as any other desired overlapping end formation can be employed if desired or found expedient.

It is also evident that various other forms, arrangements, combinations, and constructions might be resorted to without departing from the spirit and scope of our invention, and hence we do not wish to limit ourselves to the exact and specific disclosures hereof.

What we claim, is:

Connecting means between well casing sections of relatively large diameter having the end of one of said sections receiving and fitting over the end of the adjacent section to provide a seal therebetween, the overlapped end portions of the sections having alined

slots therethrough at intervals therearound, and fastening members comprising bolts having flat sided heads insertable through said aligned slots, respectively, from the exterior of the casing and rotatable to positions therein held against outward displacement therethrough, means for sealing said slots, and means for securing said members and sealing means in position clamping the overlapped casing ends together to form a joint between and connecting the sections.

Signed at Beatrice, Nebraska, this 2nd day of March, 1929.

HAROLD E. LAWRENCE.
